(57) **CLAIM**

I claim the design for a exhaust stack simulator, as shown and described herein.

DESCRIPTION

FIG. 1 is a top view of the right-side simulator of a pair of simulators in accordance with the present invention;

FIG. 2 is a top view of the left-side simulator of a pair of simulators in accordance with the present invention;

FIG. 3 is a side view of one of the simulators of a pair in accordance with the present invention;

FIG. 4 is an enlarged front view of the left-side simulator of FIG. 2 and a pair of simulators in accordance with the present invention; and,

FIG. 5 is an enlarged front view of the right-side simulator of FIG. 1 and of a pair of simulators in accordance with the present invention.
